UNITED STATES PATENT OFFICE

165,040

FAUCET HANDLE

Stephen A. Young, Delphi, Ind.

Application October 10, 1950, Serial No. 12,505

Term of patent 14 years

(Cl. D91—3)

To all whom it may concern:

Be it known that I, Stephen A. Young, a citizen of the United States, residing at Delphi, in the county of Carroll and State of Indiana, have invented a new, original, and ornamental Design for Faucet Handle, of which the following is a specification, reference being had to the accompanying drawing, forming part thereof, wherein:

Figure 1 is a top perspective view of a faucet handle, embodying my new design.

Figure 2 is a top plan view.

Figure 3 is an end view of the handle taken from the left end of Figure 4.

Figure 4 is a side view of the handle.

Figure 5 is an end view of the handle taken from the right end of Figure 4.

Figure 6 is a bottom view of the handle.

I claim:

The ornamental design for a faucet handle, substantially as shown.

STEPHEN A. YOUNG.
